UNITED STATES PATENT OFFICE

2,513,611

WIRE HELIX-FORMING CORE

Edward E. Woller, Kenosha, Wis., assignor to
Simmons Company, New York, N. Y., a corpora-
tion of Delaware

Application February 3, 1949, Serial No. 74,365

5 Claims. (Cl. 153—66)

1

This invention relates to helix-forming cores of the type employed in spring assembly machines such as are shown in Patent 2,388,106, issued October 30, 1945.

In a machine of this type the wire is pushed through the helix-forming groove by a pair of rollers arranged adjacent to the core. Wire used for this purpose, generally has to be exposed to an oil bath during the drawing thereof or is subsequently treated with oil to protect the surface against rusting. More than likely, during storage and transport of such wire particles of dust and dirt will accumulate on this oil coating. Consequently, when such a wire is pushed through the helix-forming groove the dust- and dirt-laden oil or grease is wiped off onto the core. Accumulations of such material become so excessive that frequent shut-downs of the machine are required in order to permit workmen to remove, clean, and replace the core. Obviously, such shut-downs result in temporary losses in production.

The main objects of this invention, therefore, are to provide an improved form of helix-forming core which is virtually self-cleaning; and to provide a helix-forming core of this kind which is inexpensive to manufacture and capable of being readily substituted for the helix-forming core of the type heretofore in use.

In the accompanying drawings:

Fig. 1 is a sectional elevational view of the core-mounting and wire-pushing portions of a helix-forming machine such as is shown in the aforesaid patent wherewith is associated a helix-forming core constructed in accordance with this invention;

Fig. 2 is an enlarged perspective view of this improved helix-forming core per se;

Fig. 3 is a plan view of the core in the position shown in Fig. 2;

Fig. 4 is a side elevation of the view of the core as shown in Fig. 2;

Fig. 5 is a view of the shaft directly opposite that shown in Fig. 4; and

Figs. 6, 7, and 8 are cross-sectional views of the core taken on the lines 6—6, 7—7, and 8—8, respectively, of Fig. 1.

As shown and described in the aforesaid patent 2,388,106, a helix-forming core 10 is in the form of a rod or shaft with a larger grooved section 11 and a reduced or stem section 18. The core 10 is supported in a mounting 13 in position to receive a wire 14 which is pushed through a core groove 11 by feeding rollers 15 and 16. The wire-receiving groove 11 extends from the front end of

2

the core 10 axially inward along the periphery of the larger section 11 to a point near the stem 18 where the groove is diverted into a helix terminating at the reduced or stem section 18.

5 In a core constructed in accordance with this invention, an auxiliary groove or channel 12 is formed on the larger section 11 of the core 10 diametrically opposite the groove 11 and is diverted into a helix parallel with the helical part 10 of the groove 11. This auxiliary groove or channel 12 is initiated slightly short of the front end of the shaft 10 and is somewhat larger in width than the groove 11.

15 Apertures or openings 19 are formed in the core shaft 10 providing communication radially of the shaft between the grooves 11 and 12. As will be most clearly noted from Figs. 6, 7, and 8, these apertures are tapered from the groove 11 toward the groove 12.

20 The mounting member 13 supports a tubular element 20 wherein the core 10 is secured by a set screw 21. The tubular element 20, in turn, is retained in proper position on the mounting member 13 by a set screw 22. The core 10 is positioned with the tapered inner end between the rollers 15 and 16 to receive the wire 14 therefrom. The core stem 18 is thereby located in a collar 23 mounted in a block 24 secured to the mounting 13.

25 30 During the operation of a spring assembly machine of the type shown in the aforesaid patent, the dust- and dirt-laden oil or grease, as it is wiped or scraped from the wire 14 passing through the groove 11, has a tendency to pass through the openings 19 into the groove 12. The constant scraping of such material from the wire will tend to keep a pressure on the material escaping through the apertures 19 so that such material will be forced eventually out through the end of 35 the spiral portion of the groove 12. There is, therefore, little possibility of this dust- and dirt-laden grease or oil clogging the helix-forming groove 11, thereby practically obviating the necessity of stopping the machine in order to remove and clean the coil, as so frequently has proved to be the case with the type of helix-forming core shown in the aforesaid patent.

40 45 Variations and modifications in the details of structure and arrangement of the parts may be resorted to within the spirit and coverage of the appended claims.

I claim:

1. A wire-helix-forming core of the class described comprising, a shaft having formed in its outer surface a groove terminating in a spiral

and of a size to accommodate the wire and form it into a helix when the wire is propelled through said groove, said shaft also having formed on its outer surface a discharge channel in spaced relationship with said wire-forming groove, said core having one or more transverse openings therethrough connecting said groove and said channel whereby material wiped from said wire passing through said wire-forming groove is discharged through said channel.

2. A wire-helix-forming core of the class described comprising, a shaft having formed in its outer surface a groove terminating in a spiral and of a size to accommodate the wire and form it into a helix when the wire is propelled through said groove, said shaft having a second groove formed in the surface thereof in spaced parallel relationship to said wire-forming groove, and said core having one or more transverse openings connecting said grooves whereby material wiped from said wire passing through said wire-forming groove is discharged through said other groove.

3. A wire-helix-forming core of the class described comprising, a shaft having formed in its outer surface a groove terminating in a spiral and of a size to accommodate the wire and form it into a helix when the wire is propelled through said groove, said shaft having a second groove formed in the surface thereof diametrically opposite and in parallel relationship to said wire-forming groove, and said core having one or more transverse openings connecting said grooves whereby material wiped from said wire passing through said wire forming groove is discharged through said other groove.

4. A wire-helix-forming core of the class described comprising, a shaft having formed in its outer surface a groove terminating in a spiral and of a size to accommodate the wire and form it

40

into a helix when the wire is propelled through said groove, said shaft having a second groove formed in the surface thereof diametrically opposite and in parallel relationship to said wire-forming groove, and said core having one or more transverse openings connecting said grooves and tapered toward said second groove whereby material wiped from said wire passing through said wire-forming groove is discharged through said other groove.

5. A wire-helix-forming core of the class described comprising, a shaft having formed in its outer surface a groove terminating in a spiral and of a size to accommodate the wire and form it into a helix when the wire is propelled through said groove, said shaft having a second and larger groove formed in the surface thereof diametrically opposite and in parallel relationship to said wire-forming groove, and said core having one or more transverse openings connecting said grooves and tapered toward said second groove whereby material wiped from said wire passing through said wire-forming groove is discharged through said other groove.
